(57) **CLAIM**

The ornamental design for a chair, as shown and as described.

DESCRIPTION

FIG. 1 is a front perspective view showing my new design.

FIG. 2 is a front view thereof.

FIG. 3 is a rear view thereof.

FIG. 4 is a left end view thereof.

FIG. 5 is a right end view thereof.

FIG. 6 is a top view thereof.

FIG. 7 is a bottom view thereof; and,

FIG. 8 is a second front perspective view thereof, shown in an alternate position of use.

The broken lines shown in the drawings illustrate portions of the article that form no part of the claimed design.

The small, short length broken lines in the drawings illustrate stitching pattern on surfaces of the chair that forms part of the claimed design.

The larger, wider spaced broken lines indicate that the appearance of any portion between the larger, wider spaced broken lines forms no part of the claimed design.

1 Claim, 8 Drawing Sheets
